UNITED STATES PATENT OFFICE.

BALTZAR CARL VON PLATEN AND CARL GEORG MUNTERS, OF STOCKHOLM, SWEDEN,
ASSIGNORS, BY MESNE ASSIGNMENTS, TO ELECTROLUX SERVEL CORPORATION, A
CORPORATION OF DELAWARE.

REFRIGERATOR.

Application filed October 1, 1925, Serial No. 59,906, and in Sweden December 1, 1924.

The present invention relates to refrigerator cabinets provided with refrigerating apparatus, and relates more particularly to cabinets provided with refrigerating apparatus of the type wherein the elements constitute a hermetically closed system and in which the different parts are welded or otherwise firmly and unremovably connected with one another. Certain difficulties are met with in mounting such refrigerating apparatus on or within a cabinet, said difficulties depending mainly upon the fact that the evaporator should be arranged inside the heat insulating wall of the cabinet, whereas the other parts of the apparatus should be disposed outside the wall. In refrigerating apparatus whose different parts are connected with one another by means of screw-threads or the like, the parts disposed on opposite sides of the heat insulating wall may be easily connected with each other, but in apparatus of the first-mentioned kind the welding operation cannot be conveniently performed after the different parts of the apparatus have been mounted in position in the cabinet.

The principal object of the present invention is to avoid the difficulties set forth above by providing a cabinet having a removable wall part carrying the refrigerating apparatus in such a manner that the evaporator is situated inside said wall part and within the cabinet, when said wall part is in position.

Another object of the invention is to provide a cabinet having a removable side wall portion and a refrigerating apparatus carried by said wall portion and disposed in such a manner that the evaporator is on the one side of said wall part, whereas the other parts of the refrigerating apparatus are disposed on the opposite side thereof, the pipes connecting said evaporator with the other parts of the refrigerating apparatus being utilized to support and fix the refrigerating apparatus in said wall part.

A further object of the invention is to provide a cabinet having heat insulating walls and a removable wall portion adapted to fit into an opening in one of said

walls, preferably in one of the side walls of the cabinet.

Further objects of the invention will appear from the following specification, with reference to the accompanying drawings, 55 and will be pointed out in the appended claims.

In the drawings,

Fig. 1 is a vertical section of a refrigerator cabinet according to the present invention 60 with the refrigerating apparatus mounted in place.

Fig. 2 is a section on the line II—II of Fig. 1.

Fig. 3 is a side view of the refrigerating 65 apparatus seen from the right in Fig. 2, the protecting casing being omitted. In this figure for the sake of illustration the evaporator is turned 90° in clockwise direction so as to come in the same plane as the generator 70 and the absorber.

Fig. 4 is a vertical section of another embodiment of a refrigerator cabinet according to the invention with the refrigerating apparatus mounted in place. 75

Fig. 5 is a section on the line V—V in Fig. 4.

Fig. 6 is a vertical section of a third embodiment of a refrigerating apparatus according to the invention with the refrigerating apparatus mounted in place. 80

According to the embodiment shown in Figs. 1, 2 and 3, 1 denotes the heat insulating walls of the cabinet, one of said walls 1 having a quadrangular opening into which 85 fits a door 2 of heat insulating material, said door being preferably swingably mounted on hinges 3. The refrigerating apparatus which is of the absorption type, comprises a generator 4, an absorber 5, an evaporator 6, 90 constituting the refrigerating member, and a condenser 7, said parts being connected with one another by means of pipes so as to form a hermetically closed circulating system (see especially Fig. 3). The generator 95 4 and the absorber 5 are connected by means of pipes 8 and 9, and interposed in said pipes is a double pipe heat exchanger 10 having for its object to exchange heat between the liquid passing from the absorber 5 and 100

that passing from the generator 4. The generator is heated by means of a suitable source of heat, for instance an electric heating element 11. The absorber 5 and the evaporator 6 are connected by means of pipes 12 and 13, and the generator 4 and the evaporator 6 are connected by means of a pipe 14 in which pipe the condenser 7 is inserted, having inlet 15 and outlet 16 for a cooling medium, for instance water.

The refrigerating apparatus is mounted in the door 2 in such a manner that, when the door is closed, the evaporator 6 will be inside the door 2, whereas the other parts of the refrigerating apparatus will be entirely outside the heat insulating door 2. The refrigerating apparatus is entirely supported by said door by means of the pipes 12 and 13 which connect the evaporator 6 with the absorber 5. The door is divided into two portions along the vertical plane 17 (see Fig. 2), and the edges of the portions facing each other are provided with semi-cylindrical notches embracing pipes 12 and 13. A bearing plate 18 serves to attach the refrigerating apparatus to the door 2, said bearing plate 18 being provided with holes for the pipes 12, 13 and being put on said pipes before the different parts of the refrigerating apparatus are united. The refrigerator is attached to the bearing plate 18 by means of nuts 19, 20 screwed onto the pipes 12, 13 on opposite sides of the plate 18. The bearing plate 18 is fixed on the inside of the door 2, which, on its inside, is provided with a lining 21 of sheet metal connected with the bearing plate 18 by means of screws 22 and nuts 23 in such a manner that a fluid tight joint is formed between the bearing plate 18 and the sheet metal lining 21. The bearing plate 18 together with the lining 21 form the outer wall of a brine tank 24 enclosing the evaporator 6, the remainder of said brine tank consisting of a casing 25 of sheet metal connected with the lining 21 of the door 2 by means of a fluid tight joint 26. The brine tank 24, which is filled with a liquid, the freezing point of which is lower than that of water at the same pressure, for instance aqueous glycerine, a suitable salt solution or the like, has for its object to form on the one hand a cold accumulator of great capacity, and on the other hand a large cooling surface, for which purpose the casing may be provided with cooling flanges.

In order to produce ice in the refrigerating cabinet the cold container 24 is provided with a pocket 27, preferably of quadrangular shape, said pocket 27 being provided with shelves 28 on which rest ice molds 29.

The parts of the refrigerating apparatus disposed outside the door 2 are covered by a protecting casing 30 provided with apertures 31 to effect circulation of air. Ar-

ranged between the casing 25 of the brine tank and the opposite wall of the cabinet is a shelf 32 dividing the interior of the refrigerating cabinet into an upper space 33 and a lower space 34.

The refrigerating apparatus is mounted in the following manner: The assembled apparatus provided with the bearing plate 18 is disposed on the door 2 between its halves which are then connected with each other in some way or other, and then the bearing plate 18 is screwed onto the door 2 for fixing the apparatus in firm position. Then the brine tank 24 is fixed inside the door 2 in the manner described above, whereupon the door 2 is inserted into the corresponding opening in the side wall of the cabinet.

In the embodiment shown in Figs. 4 and 5, one of the vertical walls of the cabinet is provided with a vertical groove 35 adapted to be closed by a narrow slide shutter 36 (see Fig. 5) which corresponds to the swingable door 2 in the embodiment shown in Figs. 1, 2 and 3. In this case, the apparatus is preferably connected with the removable wall part, viz the shutter 36 by means of a bearing plate 18. The whole aggregate is adapted to be pushed down in the groove 35, the evaporator 6 passing through an opening 37 in the top wall of the cabinet, which opening 37 is then closed by a loose cover of heat insulating material. The brine tank 24 may constitute a part of the aggregate as in the embodiment shown in Figs. 1, 2 or 3, but it may also be adapted to be fastened to the bearing plate 18 from within, after the aggregate has been mounted in the cabinet, or it may be permanently installed within the cabinet.

In the embodiment shown in Fig. 6, the refrigerating apparatus is disposed on the plane upper surface of the cabinet. In order to obtain an effective thermic connection between the evaporator 6 and the cooling spaces in spite of the special relation between the level of the evaporator 6 and that of the absorber 5 necessary in refrigerating apparatus of the present type, the casing 25 of the brine tank 24 is provided with an extension 40 extending downwards through an opening 41 in the upper wall of the cabinet, approximately halfway the entire height thereof. The casing 25 rests on the upper surface of the cabinet by means of a welded-on flange 42 supporting the refrigerating apparatus. The heat insulating wall of the cabinet is continued above the opening 41 by means of a cap 43 of heat insulating material, said cap 43 enclosing the evaporator 6 and the upper portion of the brine tank 24 and corresponding to the door 2 in the embodiment shown in Figs. 1, 2 and 3. The mantle of the cap 43 is provided with holes or notches for the connecting pipes 12, 13 between the evaporator 6

and the absorber 5, and is preferably formed in two semi-cylindrical halves, the edges of said halves, which face each other, lying in a vertical plane extending through said 5 holes.

What we claim as new and desire to secure by Letters Patent of the United States of America is:—

1. In a refrigerator comprising a cabinet 10 having walls of heat insulating material, a removable wall part and refrigerating apparatus carried by said wall part, said refrigerating apparatus comprising a generator, an absorber, an evaporator, a condenser 15 and pipes connecting said evaporator with the other parts of the refrigerating apparatus, said pipes passing through holes in said wall part and supporting the refrigerating apparatus, said wall part being divided 20 along a section plane extending through said holes, the evaporator being disposed inside said wall part and within the cabinet, whereas the other parts of the refrigerating apparatus are disposed outside thereof.
2. A refrigerator comprising a cabinet 25 having an inner cooling space surrounded by walls comprising insulating material and including a vertical side wall, a vertically extending removable insulated portion forming part of said side wall, a generator, an absorber and condensing means situated on the outside of and adjacent to said removable portion and supported entirely on said removable portion, said absorber and generator being disposed substantially horizontally side by side, an evaporator on the inner side of said removable portion in said cooling space and supported entirely on said removable portion, a plurality of pipes 30 connecting said evaporator and absorber passing through said removable portion and a pipe connecting said condensing means with said evaporator passing through said removable portion.
3. A refrigerator comprising a cabinet 35 having an inner cooling space surrounded by walls comprising insulating material and including a vertical side wall, a vertically extending removable insulated portion forming part of said side wall, a generator, an absorber and condensing means situated on the outside of and adjacent to said removable portion and supported entirely on said removable portion, an evaporator on the inner side of said removable portion in said cooling space and supported entirely on said removable portion, a plurality of conduits 40 connecting said evaporator and absorber, said conduits passing through said removable portion and a conduit connecting said condensing means with said evaporator, the last mentioned conduit passing through said removable portion.
4. A refrigerator comprising a cabinet 45 having an inner cooling space surrounded by walls comprising insulating material and including a vertical side wall, a vertically extending removable insulated portion forming part of said side wall, a generator, an absorber and condensing means situated on the outside of and adjacent to said removable portion and supported entirely on said removable portion, an evaporator on the inner side of said removable portion in said cooling space and supported entirely on said removable portion, a plurality of conduits 50 connecting said evaporator and absorber, said conduits passing through said removable portion and a conduit connecting said condensing means with said evaporator, the last mentioned conduit passing through said removable portion.
5. A refrigerator comprising a cabinet 55 having an inner cooling space surrounded by walls comprising insulating material and including a vertical side wall, a vertically extending removable insulated portion forming part of said side wall, a generator, an absorber and condensing means situated on the outside of and adjacent to said removable portion and supported entirely on said removable portion, an evaporator on the inner side of said removable portion in said cooling space and supported entirely on said removable portion, a plurality of conduits 60 connecting said evaporator and absorber, said conduits passing through said removable portion and a conduit connecting said condensing means with said evaporator, the last mentioned conduit passing through said removable portion.
6. A refrigerator comprising a cabinet 65 having an inner cooling space surrounded by walls comprising insulating material and including a vertical side wall, a vertically extending removable insulated portion forming part of said side wall, a generator, an absorber and condensing means situated on the outside of and adjacent to said removable portion and supported entirely on said removable portion, an evaporator on the inner side of said removable portion in said cooling space and supported entirely on said removable portion, a plurality of pipes 70 connecting said evaporator and absorber passing through said removable portion and a conduit connecting said condensing means with said evaporator passing through said removable portion.

by walls comprising insulating material and including a removable insulated wall portion, a generator, an absorber and condensing means situated on the outside of and adjacent to said removable portion and supported entirely on said removable portion, an evaporator on the inner side of said removable portion in said cooling space and supported entirely on said removable portion, a plurality of conduits connecting said evaporator and absorber passing through said removable portion and a conduit connecting said condensing means with said evaporator passing through said removable portion.

5. A refrigerator comprising a cabinet 75 having an inner cooling space surrounded by walls comprising insulating material and including a vertical side wall, a vertically extending removable insulated portion forming part of said side wall, a generator, an absorber and condensing means situated on the outside of and adjacent to said removable portion and supported entirely on said removable portion, an evaporator on the inner side of said removable portion in said cooling space and supported entirely on said removable portion, a plurality of pipes 80 connecting said evaporator and absorber at the top and bottom of each thereof, said pipes passing through said removable portion and a pipe connecting said condensing means with said evaporator, the last mentioned pipe passing through said removable portion.

6. A refrigerator comprising a cabinet 85 having an inner cooling space surrounded by walls comprising insulating material and including a vertical side wall having a stationary portion and a vertically extending removable insulated portion forming part of said side wall, hinges connecting said removable portion to said stationary portion, said removable portion being adapted to be swung about said hinges, a generator, an absorber and condensing means situated on the outside of and adjacent to said removable portion and supported entirely on said removable portion, an evaporator on the inner side of said removable portion in said cooling space and supported entirely on said removable portion, a plurality of pipes 90 connecting said evaporator and absorber and passing through said removable portion and a pipe connecting said condensing means with said evaporator passing through said removable portion.

7. A refrigerator comprising a cabinet 95 having an inner cooling space surrounded by walls comprising insulating material and including a vertical side wall, a vertically extending removable insulated portion forming part of said side wall, said removable portion including a bearing plate, a generator, an absorber and condensing means situated on the outside of and adjacent to said 100

removable portion, an evaporator on the inner side of said removable portion in said cooling space, a plurality of pipes connecting said evaporator and absorber passing through said removable portion, means to fix said bearing plate to said pipes, a pipe connecting said condensing means with said evaporator passing through said removable

portion, a brine tank surrounding said evaporator, said bearing plate forming a portion 10 of the wall of said brine tank.

In testimony whereof we affix our signatures.

BALTZAR CARL von PLATEN.
CARL GEORG MUNTERS.
